UNITED STATES PATENT OFFICE.

WILLIAM MARTINDALE, OF MANILLA, IOWA.

SHEAF-CARRIER.

No. 918,457.

Specification of Letters Patent. Patented April 13, 1909.

Application filed July 7, 1908. Serial No. 442,311.

To all whom it may concern:

Be it known that I, WILLIAM MARTINDALE, a citizen of the United States, residing at Manilla, in the county of Crawford and State of Iowa, have invented new and useful Improvements in Sheaf-Carriers, of which the following is a specification.

This invention relates to sheaf carriers for binders, the object of the invention being to provide a carrier which shall be simple in construction, and effective in its operation.

The invention consists in certain novel features of construction hereinafter more fully described and claimed.

In the accompanying drawings, Figure 1 is a top plan view of a sheaf carrier constructed in accordance with the present invention, illustrating the same in applied position upon a binder, the binder being indicated by the dotted lines. Fig. 2 is an enlarged longitudinal sectional view upon the line 2—2 of Fig. 1, illustrating the sheaf or supporting fingers in closed position. Fig. 3 is a similar view illustrating the sheaf supporting fingers in their opened position. Fig. 4 is a transverse sectional view upon the line 4—4 of Fig. 1, the figure being enlarged.

The improved sheaf carrier is adapted to be applied to harvesters and binders of any ordinary construction and comprises a rectangular frame 1 carrying a pair of spaced pivoted axles 2 and 3. Secured to these axles 2 and 3 are the sheaf supporting fingers 4 and 5. The axles 2 and 3 are each provided with oppositely extending ears or offsets 6 and 7 adapted for the reception of a connecting rod 8.

By reference to the several figures of the drawings it will be noted that the ear 6 connected to the axle 2 extends below the said axle and that the ear 7 connected with the axle 3 extends above said axle so that upon the rotation of one of the shafts the rod 8 will cause the opposite axle to rotate in an opposite direction, thus causing the fingers 4 and 5 to open away from each other. The ear 6, it will be noted by reference to the figures of the drawing is of a greater length than the ear 7, and the supporting fingers 4 carried by the axle 2 are also of a greater length than the fingers 5 carried by the axle 3. The fingers 4 are suitably inclined to provide means whereby

the sheaves upon the device may be easily slid therefrom toward the side of the machine when the carrier is in its open position as illustrated in Fig. 3, and the fingers 5 are also suitably bent to provide a substantial retarding means for the sheaves dropped by the fingers 4, so that when the device is operated the sheaves drop in a compact mass providing a substantial shock.

By the construction of arms or fingers as above described, it will be noted that the longer fingers 4 are brought more closely toward the ground than the fingers 5 when the device is operated, and consequently are more liable to contact by stones or other obstructions than the shorter fingers 5. In order to prevent the breaking of the fingers by such contacts, I have provided the fingers with a forwardly extending portion projecting from beneath the axle 2, and this portion is provided with an offset 4' projecting upwardly and connected with a transverse bar 9. This bar 9 has its end adjacent the connecting rod 8 provided with a suitable perforation, and the axle 2 is provided with a projecting finger or offset 10. The perforation provided by the bar 9 and the offset 10 are adapted for the reception of a tension spring 11. This spring 11 is adapted to retain the fingers 4 in a parallel plane with the longitudinally extending fingers 5 and is also designed to provide means for relieving the fingers of shock when contacted by an obstacle.

The axles 2 and 3 are each provided with vertically extending offsets 12, and these offsets are adapted for pivotal connection with the arms 13 and 14 of the locking device. The arms 13 and 14 are pivotally connected together as at 15 and the arm 14 is provided with an extending finger 16 which is adapted to contact and be engaged by a headed pintle 17 carried by the arm 13. By this construction it will be noted that when the arms 13 and 14 are in their locked position, as illustrated in Fig. 2 of the drawings, the supporting fingers are retained normally closed, but when one of the arms is contacted to throw the pivoted members upwardly as indicated in Fig. 3 of the drawings the supporting fingers 4 and 5 are swung open. In order to operate the locking member I have provided the side of the frame 1 adjacent the arm 3 with a suitable opening adapted for the reception of an off-

set trip member 18. This member 18 is adapted to lie normally beneath the arm 13, and upon being rotated, through the medium of a series of rods connected with a foot lever indicated by the dotted lines in Fig. 1, will swing the arm 13 upwardly upon its pivotal connection with the axle 2 thereby breaking the joint provided by the finger 16 and the headed stud 17 and swinging the fingers 4 and 5 to their open position.

In order to automatically close the fingers 4 and 5, when pressure has been released from the offset arm 18, I have provided the 15 underface of the axle 3 with a suitable eye 19, adapted for the reception of a tension spring 20. This spring 20 has its opposite end connected with a suitable staple 21 provided upon one of the sides of the frame 1. By this arrangement it will be noted that 20 the fingers 4 and 5 will be automatically closed through the medium of the spring 20 when pressure is released from the element 18 and that the arms 13 and 14 will be effectively locked so as to prevent the 25 revolving of the axles 2 and 3 and thus retain the fingers 4 and 5 in their closed position while receiving the sheaves.

While I have illustrated and described the preferred embodiment of the invention 30 as it now appears to me, it is to be understood that minor details of construction within the scope of the following claims may be resorted to without departing from the spirit or sacrificing any of the advantages of the invention.

Having thus fully described the invention what is claimed as new is:

1. The combination with a rectangular frame, a pair of horizontally arranged axles secured between two sides of the frame, downwardly inclined fingers upon the axles, the fingers extending toward and terminating in a line with each other and the fingers carried by one of the axles being of a greater length than the fingers carried by the opposite axle, ears upon the axles, a locking device comprising a pair of arms pivoted together and connected with the ears and normally adapted to prevent the axles from rotation, and means for breaking the pivoted joint of the arms to rotate the axles and swing the fingers carried by the axles.

2. The combination with a frame, a pair of spaced axles upon the frame, curved fingers carried by the axles and extending toward the axles, a connecting rod between

the axles, a latch member for the axles to normally prevent the axle from rotating, said latch comprising a pair of pivoted arms, one of said arms being provided with a finger, the opposite arm being provided with a headed stud adapted to engage the finger, and means for swinging one of the arms upwardly to disengage the finger from the headed stud to rotate the axles and to swing open the fingers carried by the axles.

3. The combination with a rectangular frame, a pair of spaced axles horizontally connected with two of the sides of the frame, downwardly curved fingers carried by the 70 axles and projecting toward each other, a connecting rod between the axles, offsets upon the axles, a pair of locking arms pivotally connected with the offsets of the axles, a foot operated device for unlocking the 75 axles, and a resilient member connected with one of the axles to return the lock and axles to their initial position.

4. The combination with a frame, a pair of spaced axles upon the frame, curved 80 fingers projecting toward each other carried by the axles, the fingers of one of the axles being longer than the fingers of the opposite axle, and said longer fingers being provided with extending portions each having an offset extension, a transverse bar connected with the offset extensions, a finger upon the axle, a tension spring connected with the finger and secured to the transverse bar, a connecting rod between the axles, laterally 90 extending ears upon the axle, a latch member for the ears, said latch member comprising a pair of arms pivotally connected together and pivotally connected with the ears of the axles, one of said arms being 95 provided with a projecting finger, the opposite arm being provided with a headed stud adapted to engage with the finger to sustain the arms in a normal parallel plane, means for swinging one of the arms to release the finger from the headed stud and for rotating the axles to swing the fingers carried by the axles open, and a resilient member connected with one of the axles and the frame for returning the fingers, axles 100 and latch members to their normal position.

In testimony whereof I affix my signature in presence of two witnesses.

WILLIAM MARTINDALE.
